UNITED STATES PATENT OFFICE.

WALTER DYER, OF PORTLAND, OREGON.

ARCH CONSTRUCTION.

1,223,266.

Specification of Letters Patent. Patented Apr. 17, 1917.

Application filed April 3, 1916. Serial No. 38,584.

To all whom it may concern:

Be it known that I, WALTER DYER, a citizen of Great Britain, residing at Portland, in the county of Multnomah and State of Oregon, have invented certain new and useful Improvements in Arch Constructions; and I do declare the following to be a full, clear, and exact description of the invention, such as will enable others skilled in the art to which it appertains to make and use the same.

My invention relates to improvements in the building of arches and analogous structures, and the main object thereof is to provide a number of arch forming sections which may be quickly and easily assembled to form the structure required, said sections being so constructed as to be effectively held in place without the use of extrinsic means, while other sections are being applied.

With this general object in view, the invention resides in certain novel features of construction and in unique combinations of parts to be hereinafter fully described and claimed, the descriptive matter being supplemented by the accompanying drawings which constitute a part of this application and in which:

Figure 1 is a perspective view of a partially completed arch constructed in accordance with the invention;

Fig. 2 is a disassembled perspective view of the parts shown in Fig. 1;

Fig. 3 is an outer side elevation of one of the arch forming members;

Fig. 4 is an inner side elevation thereof;

Figs. 5 and 6 are respectively an edge and an end view of the aforesaid member;

Fig. 7 is a detail vertical section taken on the line 7—7 of Fig. 1;

Fig. 8 is a perspective view showing a modified form thereof.

In specifically describing the construction shown in the drawings above briefly described, similar characters will be placed on corresponding parts throughout the several views and reference will be herein made to the numerous elements by their respective indices. To this end, the numerals 1 designate a pair of sleepers which will usually be employed and which will be constructed of cement or other appropriate masonry, and in some cases a similar bottom 2 will extend

55 between the sleepers 1 as shown, this bottom

being preferably employed only when the improved arch is to be used as a culvert, sewer or the like.

Spanning the space between the sleepers 1 is a rigid arch 3 which may be formed of one piece as shown or of a number of sections rigidly secured together. It is essential, however, that said arch be provided with a flange 4 extending from one of its edges and continuing from one end thereof to the other, said flange having in its upper surface a longitudinally extending groove 5.

Abutting the aforesaid edge of the arch 3 and supported by the flange 4 thereof is a second arch 6 which is composed of a number of intermediate members 7 and a pair of end members 8. Each member 7 consists of an inner rectangular section 9 and an outer similarly shaped section 10, the inner and outer sections being offset both transversely and longitudinally from each other in a diagonal direction and overlapping approximately one-fourth of their areas as disclosed at 11. The laterally extending portion of the outer section 10 is provided with a longitudinally extending rib 12 on its inner face for reception in the groove 5, while the laterally extending part of each of the lower sections 9 has formed in its outer surface a longitudinally extending groove 5a. As will be clear from the drawings, when the arch is being constructed, the laterally projecting parts of the members 7 of the arch 6 will overlie the flange 4 of the arch 3, and the longitudinally extending portions of the aforesaid members will overlap.

The end members 8 are very similar in construction to the members 7, but they are provided with no longitudinally extending portions on their lower ends in order that they may properly rest on the sleepers 1.

Abutting the arch 6 is a similar arch 6a constructed of intermediate members 7 as above described and end members 8. The ribbed upper sections of the members 7 of said arch 6a overlap the grooved lower sections of the arch 6 as shown, with the ribs received in the grooves, and the end members 8 are of such a length as to cause the numerous members of the two arches to break joints at their ends to strengthen the structure.

Any number of arches 6 and 6a may be employed, and these arches will alternate as will be readily understood. After so

constructing the complete arch, of the numerous members 7 and 8 which will preferably be formed of cement, liquid cement will be poured or spread over the entire structure and run into the interstices between the numerous structural units of which said arch is composed. This having been done, if the device is to be used as a culvert beneath a roadway or the like, earth may be piled over the same, the weight of this earth as well as the liquid cement above referred to serving to effectively hold all parts of the arch in assembled relation.

15 It will be readily understood that my invention may be well used as a tunnel lining and that if this be done, earth, rock or cement may be packed between the lining and the wall of the tunnel. Also, I may construct the numerous members of the arch of cast metal as indicated at 7^a in Fig. 8, and may use these members as molds or forms in constructing arches of cement and the like, it being obvious that after the material has hardened sufficiently the form may be removed and advanced for further use.

Particular emphasis is laid upon the fact that the sections 9 and 10 overlap one-fourth of their areas, and also upon the interlocking ribs and grooves. By this arrangement, the individual members 7 will remain in position as they are applied without supporting means other than that provided by the projecting sections of adjacent members. This is obviously of great advantage and as stated results primarily from the proportions shown and described and from the interlocking ribs and grooves. However, the same result can be obtained by constructing the members of the aforesaid proportions but by eliminating the ribs and grooves.

I am aware that I am not the originator of an arch forming member comprising inner and outer sections straight transversely, curved longitudinally and offset diagonally in both longitudinal and transverse direc-

tions, this broad idea being disclosed in U. S. Patent Number 546245 of September 10, 1895 (see Fig. 10). However, the proportions of the block shown in this patent are not such as to allow each individual block to be self sustained as it is applied, as is the case when constructing the arch forming members of the proportions shown and described in the present application. This change in proportion is therefore considered a salient feature of the present invention, and its combination with the ribs and grooves described is also important.

85

From the foregoing taken in connection with the accompanying drawings, the construction, manner of operation and advantages of my improvements will be readily understood without requiring a further explanation, but in conclusion I will state that although the sections 9 and 10 have been shown, described and claimed as strictly rectangular and as overlapping exactly one-fourth of their areas, minor changes in shape and proportion may be made within the scope of the invention.

I claim:—

A self sustained block for building arches comprising an inner elongated rectangular half curved in longitudinal section and straight in transverse section, and an outer elongated rectangular half also curved in longitudinal section and straight in transverse section, the two halves being overlapped and integrally joined at one corner and being offset both longitudinally and transversely from each other with one side edge of each half disposed on the longitudinal center of the other half and with one end disposed on the transverse center thereof.

In testimony whereof I have hereunto set my hand in presence of two subscribing witnesses.

WALTER DYER.
